(57) **CLAIM**

I claim the ornamental design for a paper towel, as shown and described.

DESCRIPTION

FIG. 1 is a front elevational view of an unfolded paper towel showing my design, wherein the line down the middle

represents the fold line of the paper towel; the rear elevational view being a mirror image of the view shown in FIG. 1.

FIG. 2 is a sectional view taken along lines 2—2 of FIG. 1.

FIG. 3 is a sectional view taken along lines 3—3 of FIG. 1.

FIG. 4 is a perspective view of a paper towel of the FIG. 1.

FIG. 5 is a front elevational view of the paper towel of FIG. 1 when the paper towel has been folded. The rear elevational view being a mirror image of the view shown in FIG. 5.

FIG. 6 is a sectional view taken along lines 6—6 of FIG. 5.

FIG. 7 is a sectional view taken along lines 7—7 of FIG. 5.

FIG. 8 is a front elevational view of two of the paper towels of FIG. 1 interwovenly stacked.

FIG. 9 is a sectional view taken along lines 9—9 of FIG. 8.

FIG. 10 is a front elevational view of an unfolded second embodiment of a paper towel showing my design, wherein the line down the middle represents the fold line of the paper towel; the rear elevational view being a mirror image of the view shown in FIG. 10.

FIG. 11 is a sectional view taken along lines 11—11 of FIG. 10.

FIG. 12 is a sectional view taken along lines 12—12 of FIG. 10.

FIG. 13 is a perspective view of a paper towel of the FIG. 10.

FIG. 14 is a front elevational view of the paper towel of FIG. 10 when the paper towel has been folded. The rear elevational view being a mirror image of the view shown in FIG. 14.

FIG. 15 is a sectional view taken along lines 15—15 of FIG. 14.

FIG. 16 is a sectional view taken along lines 16—16 of FIG. 14.

FIG. 17 is a front elevational view of two of the paper towels of FIG. 10 interwovenly stacked; and,

FIG. 18 is a sectional view taken along lines 18—18 of FIG. 17.

The broken lines showing a second paper towel in FIGS. 8, 9, 17 and 18 are for illustrative purposes only and form no part of the claimed design.
